UNITED STATES PATENT OFFICE.

MICHAEL P. ENNIS, OF RAHWAY, NEW JERSEY, ASSIGNOR TO THE BARBER ASPHALT COMPANY, OF PHILADELPHIA, PENNSYLVANIA, A CORPORATION OF WEST VIRGINIA.

SHINGLE.

Application filed February 1, 1922. Serial No. 533,189.

To all whom it may concern:

Be it known that I, MICHAEL P. ENNIS, a citizen of the United States, residing at Rahway, in the county of Union and State of New Jersey, have invented certain new and useful Improvements in Shingles, whereof the following is a specification, reference being had to the accompanying drawings.

This invention relates to roof coverings, 10 with particular reference to shingles constructed of fibrous material, impregnated with bituminous substances to render the shingles flexible, non-porous and weather-proof.

15 An object of the invention is to provide a shingle of a new and novel construction by virtue of which the shingles may be laid in courses, and the shingles of each course interlocked mutually to hold their edges flat 20 against the roof, thereby precluding to a great extent the entrance and accumulation of moisture and snow beneath the shingles and enhancing the durability of the roof covering so constructed.

25 These and other objects are accomplished through the medium of several preferred structures embodying my invention, to be hereinafter described and particularly pointed out in the claims.

30 In the accompanying drawings:

Fig. I is a view in plan of a fragment of a roof covering constituting an assemblage of my improved roofing shingles.

Fig. II is a view in section taken on the 35 line II—II of Fig. I.

Fig. III is a view in perspective of a shingle unit illustrating more clearly the formation thereof.

Fig. IV is a view in plan of a fragment of a roof covering constructed of shingles embodying a slightly modified construction to 40 secure an interlocking engagement between the courses as well as between the shingles of a course.

45 Figs. V and VI are views in section taken on the line V—V and VI—VI of Fig. IV; and

50 Fig. VII is a view in perspective of a unit shingle of the type shown in the assemblage of Fig. IV.

With reference to Figs. I, II, and III, an individual or unit shingle is indicated at 55 10, and consists of a section or sheet of waterproofed and weatherproofed fibrous material such as paper, felt or the like,

preferably quadrangular in formation, and having two opposed edges bent or folded over to form the interlocking flanges 11, which are thus directed toward each other. As shown in the drawings, the sheet of material, previous to folding, is slightly oblong, so that when the edges are folded over, the resultant shingle will be substantially square. The roof covering is formed by laying these shingles in courses, with their 60 folded edges disposed at right angles to the run of the course, so that the flanges of adjacent shingles may be interlocked, as shown in Fig. II, by receiving the flange of one shingle between the flange and body portion of the adjoining shingle. The shingles are secured to the roof by driving suitable fastening elements 12, preferably through the interlocked flanges. 65

I have illustrated in Figs. IV to VII of 70 the drawings, a slightly modified arrangement of shingles, one of which is shown in Fig. VII, and consists of a sheet or section 13 of impregnated fibrous material of a flexible nature, having a pair of opposed 75 sides incised at 14 and the edges of the shingle between said incisions and one end thereof bent or folded over to form the lower locking flanges 15, and the edges between the opposite end of the shingle and 80 the incisions folded over in a reverse direction to form the upper locking flanges 16. It will be noted that the incisions are preferably made nearer one end of the shingle, 85 so that the lower locking flanges 15 are shorter than the upper locking flanges 16. When covering a roof with the shingles, 90 they are laid in courses with their folded edges running between the ridge and the eaves, the shingles of each course interlocking, one with another as shown in Fig. V, 95 from which it will be seen that the upper flanges 16 of one shingle are interlocked with the lower flanges 15 of an adjoining shingle. As a result, the edges of the shingles are not even, but staggered so that a finished course is somewhat zig-zag in 100 formation, with the flanged edges of alternate shingles 17 overlapping the flanged edges of those in between designated 18. 105

The upper flanges 16 of said alternate or overlapping shingles 17 are thus left free, so as to interlock with the lower flanges of the shingles 18 of the next course. For the sake of clearness, the shingles 17 are 110

hereinafter termed overlapping shingles, to differentiate them over the shingles 18 of the same course, hereinafter termed the underlying shingles. The second course is laid as specified above, the underlying shingles 18 of the second course interlocking with the overlapping shingles 17 of the first course. In this manner adjoining shingles of the same course are mutually interlocked, and the shingles of one course are interlocked with those of the next course. An arrangement of this kind is obviously self-sustaining and resists the separation or dislodgment of its aggregate parts as effectively as though it were an integral structure, at the same time supplying an ornamental architectural effect coupled with the more substantial property of protection from the weather, by virtue of the numerous thicknesses of material resulting from the overlapping of the shingles at frequent points. In the assemblage of Fig. I, the joints of one course preferably alternate with the joints of an overlapping course, while in the case of the second form, as shown in Fig. IV, the joints of one course are necessarily superposed over the joints of the next course. Slightly varying visual effects are thus obtainable.

Having thus described my invention, I claim:

1. As a new article of manufacture, a covering shingle of weather proof flexible material having reciprocally extending pairs of opposed folded over flanges for interlocking engagement with the complementary locking flanges of adjacent underlying and overlapping shingles.

2. As a new article of manufacture, a

covering shingle of flexible weather proof material having each of a pair of opposed edges formed integrally with flanges directed toward one face of the shingle and folded substantially flat thereagainst, and a second set of flanges directed toward the reverse face of the shingle and likewise folded substantially flat thereagainst, whereby the adjoining shingles of a course may be mutually interlocked by lapping the edges of alternate shingles over the shingles therebetween, and by inter-engaging a pair of flanges of said alternate shingles with the flanges of the shingles of an overlapping course to retain the overlying and underlying shingles against separation.

3. As a new article of manufacture, a covering shingle formed of weather proof flexible material having each of a pair of opposed edges incised to divide said edges and the material at one side of the incisions folded over in one direction substantially against the side of the shingle, and the material at the opposite side of the incision folded over in a reverse direction against the corresponding side of the shingle to form two sets of opposed interlocking flanges adapted to inter-engage complementary flanges on underlying and overlapping shingles.

In testimony whereof, I have hereunto signed my name at Maurer, N. J., this 26th day of January, 1922.

MICHAEL P. ENNIS.
